UNITED STATES PATENT OFFICE.

RUSSELL H. BURR, OF WEST MERIDEN, CONNECTICUT, ASSIGNOR TO
C. ROGERS & BROS., OF SAME PLACE.

DESIGN FOR COFFIN-SCREW HEADS.

Specification forming part of Design No. 8,037, dated February 2, 1875; application filed January 22, 1875.
[Term of Patent 7 years.]

CASE A.

To all whom it may concern:

Be it known that I, RUSSELL H. BURR, of West Meriden, in the county of New Haven and State of Connecticut, have invented a new Design for Coffin-Screw Head; and I do hereby declare the following, when taken in connection with the accompanying drawings and the letters of reference marked thereon, to be a full, clear, and exact description of the same, and which said drawings constitute part of this specification, and represent, in—

Figure 1, plan or top view; Fig. 2, side or front view.

This invention relates to a design for the head of the article known in the trade as coffin-screws—that is, the screw by which the top of coffin is screwed; and the invention consists, first, in the head of the screw in the form of a cross; second, in the screw-plate, its two ends terminating in the form of a cross.

The screw-head consists of a base, *a*, on which stands a cross, the arms serving as a convenient means for turning the screw. The cross may be of any of the various forms, the

essential feature of the design being the outline form of a cross standing on a base as the head of the screw. Under these screw-heads a plate is placed, as shown in the illustration. This plate terminates at each end in the form of a cross, this peculiar form of the plate constituting the essential feature of the second part of this design, but irrespective of the style of the cross.

These parts—plate and screw-head—are intended to correspond and be used together; but the plate may be used with a different head, or vice versa.

I claim—

1. The design for coffin-screw head, as herein described, and shown in the accompanying illustration.

2. The design for coffin-screw plate, as herein described, and shown in the accompanying illustration.

RUSSELL H. BURR.
